UNITED STATES PATENT OFFICE.

LEONARD HENKLE, OF ROCHESTER, NEW YORK.

LANTERN.

SPECIFICATION forming part of Letters Patent No. 225,983, dated March 30, 1880.

Application filed December 1, 1879.

To all whom it may concern:

Be it known that I, LEONARD HENKLE, of Rochester, in the county of Monroe and State of New York, have invented a new and useful

5 Improvement in Lanterns, which improvement is fully set forth in the following specification and accompanying drawings, in which—

Figure 1 is a side elevation; Fig. 2, a vertical section of the top part of the lantern; Fig. 3, 10 a plan of the globe-base; and Fig. 4, a central section of the latter, as indicated by the dotted line in Fig. 3, Figs. 2, 3, and 4 being drawn to a scale larger than that of Fig. 1.

My invention consists in certain improvements in barn or railroad hand-lanterns; hereinafter described, and particularly pointed out in the claims.

In the drawings, A is the globe, B the oil-reservoir, C the air-supply tubes, D the cone, 20 and F the bail, of an ordinary hand-lantern.

An ordinary cylindrical part, G, rises centrally from the oil-reservoir, upon which is fitted the cone, said cylindrical part and cone inclosing an ordinary vertical wick-tube.

25 Upon the horizontal shoulder of the cone rests a circular globe-base, J, which consists, substantially, of a horizontal circular plate, b, Figs. 3 and 4, provided with a central orifice fitting upon the cone, and two concentric 30 flanges, d and h, the bottom end of the globe resting partly within and upon the outer flange, d, as shown in Fig. 1. The flange d is perforated with small holes a, through which air may flow to the interior of the globe, to convey 35 away the heat of the flame, which may be thrown against the interior surface of the globe when the lantern is swung about, as in railroad practice. The flange h serves as a break-wall to deflect the currents of air upward, as indicated by the arrows in Fig. 1, and prevent their passing inwardly to the flame.

The plate b, at its inner edge, has two raised parts, c c, on opposite sides of the cone, formed for the purpose of allowing air to flow upward 45 over the outside of the cone to the upper portion of the flame for the purpose of completing the combustion. (Fully shown in Fig. 4.) The inner edges of the parts c c are cut to a larger circle than the flat sectors of the plate b between them, to increase the air-openings n, formed by said parts or sectors c c.

At some little distance above the upper ends of the tubes C is secured a horizontal oval plate, L, which supports a vertical cylindrical rim, P.

55 Within the rim P is telescoped another cylindrical part, O, which may be slid up or down, as indicated by dotted position, said part O supporting, at some little distance above, a dome, S, upon standards g.

60 The slide O has cut in its opposite sides two right-angled slots, e, as shown in Fig. 2, which figure represents the top part of the lantern as sectioned along the line k in Fig. 1.

65 f are two pins projecting inwardly in horizontal positions from the rim P through the slots e, as shown. The rim P has a strip cut from its lower edge, about one-half way around, to form an opening, T, on one side, to allow the top end of the globe to be swung into 70 place, as indicated in Fig. 2. When the inner slide, O, is pressed down, it closes the said opening in the rim P and completely surrounds and retains the top end of the globe after the same has been brought to position. 75

70 The dotted position of the slide O in Fig. 2 shows the same when pressed down with its lower edge upon the bead of the globe.

80 l are two inclined portions of the upper edge of the slide O, up along which the pins f ride when the slide O is pressed down and slightly rotated in the direction indicated by the arrow i. As the pins f slide up the inclines l, the part O is pressed more firmly down upon the bead of the globe, holding it securely between said part and the base-piece J, above described.

85 p p are two U-shaped pieces of sheet metal (the right-hand one being partly sectioned away) bent around the tops of the tubes C, the parallel parts of which reach to and are fastened upon the rim P. The upper edges of the pieces p p are closely joined to the under surface of the plate L, their use being to prevent currents of air from passing horizontally across 90 the ends of the tubes, which currents, if sufficiently strong, would extinguish the flame. 95

100 s s are two sloping roof-shaped wind-guards straddling the tubes, extending a half-inch laterally out from the same, which tend to break the air as the lantern is swung in the direction of the plane of the tubes. x x are similar,

but nearly vertical, wind-guards, (the right-hand one being sectioned in Fig. 1,) assisting the guards *s s* to break the air as the lantern *s* is swung as above. These guards correspond 5 in width at the top to that of the guards *s s*, to which they are secured, and taper toward the bottom ends to correspond to the diameters of the tubes *C*, to which they are also secured, having stiffening-flanges turned up at right 10 angles along their edges.

t t are two vertical webs extending inwardly from the inner surfaces of the tubes toward the globe, which extend somewhat above the mouths of the tubes, as shown at the right-hand 15 side in Fig. 1, said webs respectively dividing equally the guards *x x*, above described. These webs serve to check and break currents of air passing horizontally through between the tubes and the globe, which currents, unob- 20 structed, would tend to extinguish the flame by drawing the air up through the tubes. These several wind-guards, together with the plate *L*, completely protect the upper open ends of the tubes from violent currents of air 25 proceeding from any direction, breaking the same and permitting the flame to draw its supply of air from a comparative calm or statical air about the mouths of the tubes, whether in

windy weather or during violent swinging of the lantern in use.

30

I claim as my invention—

1. In combination with the vertical sliding piece *O*, telescoped within a band or shell, *P*, the said band or shell *P*, having a belt cut from its edge one-half around, leaving an opening, *T*, for the purpose of allowing the top end 35 of the globe to be carried into place, substantially as shown.

2. The combination of the cylindrical rim *P*, having an opening, *T*, substantially as de- 40 scribed, provided with pins *ff*, and the inner slide, *O*, provided with angle-slots *e* and inclines *l*, substantially as shown.

3. In combination with the pipes *C C* and plate *L*, the wind-guards *p, s, t*, and *x*, when 45 arranged and combined substantially as de- scribed and shown.

4. The globe-base *J*, provided with concentric flanges *h* and *d* and a central orifice to receive the cone, and having raised parts or 50 sectors *c c*, for the purpose of forming air- openings *n n*, substantially as shown.

LEONARD HENKLE.
